[57] CLAIM

The ornamental design for a change stroller, as shown and described.

DESCRIPTION

FIG. 1 is a front elevational view of the change stroller showing our new design, with wheels shown in broken lines. The broken line showing of the wheels is for illustrative purposes only and forms no part of the claimed design;

FIG. 2 is a back elevational view thereof;

FIG. 3 is a left elevational view thereof;

FIG. 4 is a right elevational view thereof;

FIG. 5 is a top plan view thereof;

FIG. 6 is a bottom plan view thereof; and,

FIG. 7 is an isometric view thereof.
